UNITED STATES PATENT OFFICE.

ORVILLE G. HALLIBURTON, OF CHICAGO, ILLINOIS.

OIL-BURNER.

1,218,647.

Specification of Letters Patent. Patented Mar. 13, 1917.

Application filed December 1, 1916. Serial No. 134,297.

To all whom it may concern:

Be it known that I, ORVILLE G. HALLIBURTON, a citizen of the United States, and a resident of Chicago, in the county of Cook 5 and State of Illinois, have invented certain new and useful Improvements in Oil-Burners, of which the following is a specification.

My invention relates to oil burners, and 10 more particularly to such as include therewith means for generating gas from the oil and for commingling air and gas in advance of the burning operation. While the present improvements may be employed elsewhere 15 than in the fire box of the ordinary stoves and ranges, the illustrated embodiment of the same is in a form especially adapted for such use, thereby substituting for coal or wood in such fire boxes liquid fuel yielding 20 a flame of burning gas.

The principal objects of these improvements are to provide an oil burner of the general class described which is of high efficiency, of simple construction, which has 25 parts readily removable, as for cleaning or repair, and which may be easily operated. A specific object is to provide means in such burners for varying proportionately the 30 amount of air to be commingled with the gas whereby a desired character of flame may be maintained when the flame is high, medium, or low; and, further, to provide means for simultaneously controlling the 35 supply of mixed gas-and-air to the burner head and the supply of air to the mixing chamber. A further specific object is to improve the commingling of gas and air prior to combustion in a device of the character 40 described. Another object is to improve the construction, association and arrangement of parts whereby the complete structure may occupy relatively small space, and whereby 45 a high efficiency is attained by such construction and arrangement. Further objects and advantages will appear hereinafter.

In the accompanying drawings, which form a part of this specification, I have illustrated a preferred embodiment, arrangement and construction of parts for carrying the 50 present improvements into operative effect. In these drawings, Figure 1 is a top plan of the device, one of the burner heads being shown in section and the gas generating tube being broken and shown in dotted lines for 55 clearness of illustration:

Fig. 2 is an end elevation as viewed from the left hand end of Fig. 1;

Fig. 3 is a rear side elevation, a portion of one of the burners being broken away to show interior parts; and

Fig. 4 is a medial transverse section as on the line 4—4 of Fig. 3 viewed in the direction of the arrows.

The substantially horizontally disposed base or support 10 having depending legs 11 65 is suitably an iron casting, the legs 11 being adapted to rest upon the fire box grate of the stove or range or upon any other suitable support. In order that several flames may be employed for heating purposes at the 70 same time I provide a plurality of burner heads, as 12, 12, a description of one thereof sufficing for both. Such burner head comprises a top plate 14, a bottom plate 15, an inner perforated side wall 16, and an outer 75 perforated side wall 17, the several walls being spaced apart to provide a hollow interior for commingling gas and air, the top and bottom walls 14 and 15 preferably being annularly recessed as at 18, 19, 20 and 21 to 80 accommodate edge portions of the walls 16 and 17, these burner head parts being held in assembled relation by screws 22. Each of the burner heads 12, 12 is held upon the support 10 by a metallic bracket 25 and bolts 85 26 and 27.

A manifold 30 is substantially horizontally disposed to the rear of the main support 10 and has upturned extremities contacting the bottom plates 15 respectively. 90 Bolts 31 secure the manifold rigidly in association with the burner heads. An opening 33 in each bottom wall 15 is in communication with the hollow interior of the manifold. A sliding plate valve device 35, of 95 arcuate shape, is movably positioned upon each bottom wall 15. A lever 36 secured to the plate 35 and traveling in an arcuate slot 37 in the bottom wall 15 is adapted to move the valve device 35 so as to open or close, 100 wholly or in part, the opening 33, thus controlling the supply of mixed gas and air to the burner head.

The manifold 30 opens into a mixing chamber 40 which depends from the manifold and turns forward preferably above the horizontal plane of the bottom of the legs 11. The walls forming the manifold 80 and mixing chamber 40 are formed as a 105 single casting of gray iron.

110

The manifold 30 has an opening 42 in the top thereof registering with an opening leading to the hollow interior 43 of the gas-generating burner 44. This generator part 5 44 is also suitably a casting. For holding the core to provide the hollow interior 43 it is advantageous to leave a circular opening in each end of the pattern of the burner part 44, and subsequently close these openings in the casting as by means of plugs 45, 45 (Fig. 3). A plurality of preferably transverse narrow slot-like openings 46 are formed in the top portion of the burner device 44 to the hollow interior thereof where- 10 by mixed gas and air from the manifold 30 will issue from these burner openings 46. I provide also two trough-like recesses 47, 47 longitudinally of the generating burner 44 adapted to hold asbestos or the like 48, 20 which is saturated with the combustion liquid and ignited in order to start the operation of the device. Other recesses 50 for containing asbestos or the like 51 are formed in the main support 10, the combustion liquid also being applied to these auxiliary primary generating burners in order further to heat the gas generating tube initially.

The gas generating tube 52, suitably an 30 iron pipe, is positioned immediately above the generator burner 44. One arm 53 thereof extends substantially over one of the asbestos generator burners 51 and then turns downward, as at the part 53^a thereof, suffi- 35 ciently away from the flame area where a union or any approved form of connection 54 unites this generator pipe with the oil supply pipe 55, a valve 56, understood to be outside the stove or range, controlling 40 the supply of the fuel oil to the generator pipe. It is to be understood that a supply of fuel oil, such as kerosene, for operating the device is contained in a suitable tank and flows by force of gravitation or by air 45 pressure within the tank to the valve 56.

Another extension 58 of the generator pipe 52 is turned substantially over the other one of the asbestos generator burners 51 and is then turned downward as at the part 59 thereof. The end of the extension 59 is closed, as at 60, by any suitable wall or plug. A small hole 61 is formed in the pipe 59 in such position that gas issuing therefrom is directed substantially centrally into the 55 horizontal leg of the mixing chamber 40.

Means for supplying air to the mixing chamber to be commingled with the gas issuing thereinto from the hole 61 comprise the hollow coupling piece 63 held upon the 60 mixing chamber 40 as by a set screw 64. A slanting opening 65 is formed in the top wall of this piece 63 whereby the pipe extension 59 may pass into the hollow interior and rest upon the bottom portion there- 65 of. No other holding means are required

for maintaining the generating pipe 52 and its several extensions in the desired operative position. Two hollow arms 66 extend from the head piece 63, each thereof toward one of the legs 11, these extensions 66 preferably being somewhat flattened so that the opening 67 (Fig. 2) at the end of each thereof is substantially of the same shape and area as is the opening 33 in the bottom wall of each of the burners 12 (Fig. 1).

A lever 70 is pivoted, as by a shouldered screw 71, to the inner wall of each of the legs 11, each lever 70 having the slot 72 in which the operating lever 36 interfits and is adapted to travel as the lever 70 is pivotally moved. A plate-like closure or valve device 74 is carried by the lower end of the lever 70.

From this construction it will be apparent that if the lever 36 is moved so as to open or close, wholly or in part, the opening 33 in one of the burners the air intake opening 67 (Fig. 2) below it will be opened or closed to the same extent. By this simple construction I provide means for simultaneously varying the amount of air entering the air-intake opening 67 proportionate to the amount of combined gas-and-air being consumed, or, in other words, proportionate to the amount of gas issuing into the burner head or heads 12, and thus the same character of flame issuing from the burners 12, 12, may be maintained whether the flame is high, medium or low.

It is pointed out that to secure the advantageous substantially non-smoking blue flame 100 at the burner heads, as 12, and which the present apparatus is adapted to provide, the amount of air mixed with the gas in the mixing chamber must be suitably proportioned. If too little air is mixed with the 105 gas a smoking yellowish flame will issue from the burner heads, while if too much air is supplied a reddish flame will result. I have found from experiment that where the air opening 67 is substantially of the 110 same area as the gas-and-air opening 33 in the burners the desired blue flame will result, and I therefore modify these openings proportionately by means of the two closures 115 35 and 74 so that the same ratio will exist between the respective effective areas of the openings 33 and 67 in all operative positions of these closures 35 and 74. When both burner heads 12, 12 are operating at full capacity, that is, with the ports 33 fully 120 opened, both the intake ports 67 are also fully opened. In case it should be desired to cut down the gas at one of the burner heads 12, 12, so that only a small flame is being used at such one while the other burner 125 head is still operating at full capacity, the desired proportion of air to gas in the mixing chamber is still maintained. It is pointed out, however, that in the latter case, if the supply of fuel remains the same, the 130

flame issuing from the burner operating at full capacity will be increased owing to the fact that it is now receiving more gas than when both burners were operating at full capacity. In such case the person operating the device may desire to cut down the supply of liquid fuel by closing to some extent the valve 56. Thus the valve 56 may be operated to control the amount of gas actually being consumed from time to time without prejudice to the maintainance of the desired character of flame at the burner heads 12, 12. The flame at one burner head may, of course, be cut off entirely by moving the lever 36 of that head. This lever 36 may be moved by any suitable rod in the operator's hand. In practice such implement is usually the stove lid lifter.

In order to provide a thorough mixing and commingling of the gas and air in the mixing chamber 40 whereby a uniform character of flame may issue from the burner heads I provide means in the mixing chamber for giving the gas and air currents a somewhat circular motion, these means comprising a piece of light-weight sheet metal 76 twisted spirally. This part 76 can be readily inserted in the mixing chamber 40 and it requires no holding means other than a slight spring pressure which it may exert against the mixing chamber walls for maintaining it in its desired location.

In beginning operations the asbestos or similar material 48 and 51 is saturated with the fuel oil, or with any suitable readily combustible liquid, such as alcohol. Upon being ignited the flames issuing therefrom heat the portions 52, 53 and 58 of the gas generator tube. After these parts have been sufficiently heated the liquid fuel is turned on at the valve 56 whereupon on reaching the heated portions of the generator tube the oil is volatilized and issues into the mixing chamber at the hole 61 of the pipe 59. The gas naturally proceeds to the generating burner 44 and issues from the burner openings 46, where it is ignited from the flame still issuing from the asbestos 48 and the flame thereof plays upon the generating pipe 52, heating it further and more thoroughly volatilizing fuel oil therein. If a lever 36 is now operated to open the ports 33 and 67 the burner head 12 receives gas which issues from the apertures of the side walls 16 and 17, and air now being admitted into the mixing chamber the flame promptly turns to the desired blue color and is available for the desired purpose. The flame issuing from the side walls 17 contiguous to the generating tubes 53 and 58 coöperates with the generating burner 44 in inducing a continuous volatilization of the oil. As the flame from the burner heads is reduced, the volatilization is cut down, and the requirement for air lessened.

While I have illustrated and described a preferred embodiment of these improvements, the invention is not limited to the exact construction or arrangement of parts specifically illustrated and described, and I 70 contemplate all modifications thereof as fall within the scope of the appended claims.

I claim:

1. In an oil burner of the character described, the combination of a pipe adapted to be secured to a source of liquid fuel supply, valve means for controlling the flow of liquid from said source, a gas generator adapted to receive liquid fuel from said valve means, means in association with said generator forming a mixing chamber for gas and air, a gas burner head, means forming a conduit between said mixing chamber and said burner head, and means for simultaneously controlling the supply of air to said mixing chamber and the supply of mixed gas-and-air to said burner head. 75

2. In an oil burner of the character described, the combination of a pipe adapted to be secured to a source of liquid fuel supply, valve means for controlling the flow of liquid from said source, a gas generator adapted to receive liquid fuel from said valve means, means in association with said generator forming a mixing chamber for 80 gas and air, a gas burner head, means forming a conduit between said mixing chamber and said burner head, means for varying the amount of mixed gas-and-air passing to said burner head, and means under the control of said gas-and-air varying means for proportionately and simultaneously varying the amount of air passing to said mixing chamber whereby a blue flame of various degrees of strength may be produced at said 85 burner head. 90

3. In an oil burner of the character described, the combination of a pipe adapted to be secured to a source of liquid fuel supply, valve means for controlling the flow of liquid from said source, a gas generator adapted to receive liquid fuel from said valve means, means in association with said generator forming a mixing chamber for 100 gas and air, a gas burner head, means forming a conduit between said mixing chamber and said burner head, a valve for controlling the supply of gas-and-air to said burner head, and a valve for controlling the supply of air to said mixing chamber, said valves being connected together whereby the operation of one thereof operates the other thereof. 105 110 115

4. In an oil burner of the character described, the combination of a gas generator, 120 means in association with said generator forming a mixing chamber for gas and air, a gas burner head, means forming a conduit between said mixing chamber and said burner head, a sliding valve within said 125 130

- burner head for controlling the supply of gas-and-air to said burner head, means for controlling the supply of air to said mixing chamber, and means for simultaneously operating said sliding valve and said air-controlling means.
5. In an oil burner of the character described, the combination of a gas generator, means in association with said generator forming a mixing chamber for gas and air, a gas burner head, means forming a gas-and-air conduit between said mixing chamber and said burner head, means forming an air conduit extending from said mixing chamber, said air conduit having an opening for the passage of air thereinto, valve means for controlling the supply of gas-and-air to said burner head, a pivoted lever having a closure thereon adapted to pass in close association with the air opening in said air conduit and to open and close the same, and a connection between said valve means and said lever adapted to move said lever to open and close said air opening when said valve means are operated.
6. The combination of a substantially horizontal support, a pair of burner heads carried thereby, a substantially horizontally disposed manifold in communication with each of said burner heads, an elongated gas generating burner above said manifold and in communication therewith, a pipe for liquid fuel having a portion thereof above said generating burner, a mixing chamber below said support, said fuel pipe having an opening whereby gas in said fuel pipe is directed into said mixing chamber, and means for admitting air into said mixing chamber.
7. The combination of a substantially horizontal support, a pair of burner heads carried thereby, a substantially horizontally disposed manifold in communication with each of said burner heads, an elongated gas generating burner above said manifold and in communication therewith, a pipe for liquid fuel having a portion thereof above said generating burner, a mixing chamber below said support, said fuel pipe having an opening whereby gas in said fuel pipe is directed into said mixing chamber, means for admitting air into said mixing chamber, and valve means for controlling the flow of mixed gas and air into said burner heads respectively.
8. The combination of a substantially horizontal support, a pair of burner heads carried thereby, a substantially horizontally disposed manifold in communication with each of said burner heads, an elongated gas generating burner above said manifold and in communication therewith, a pipe for liquid fuel having a portion thereof above said generating burner, a mixing chamber below said support, said fuel pipe having an opening whereby gas in said fuel pipe is directed
- into said mixing chamber, means for admitting air into said mixing chamber, and valve means for simultaneously controlling the flow of mixed gas-and-air into one of said burner heads and the flow of air into said mixing chamber.
9. In an oil burner of the character described, the combination of a gas generator, a burner head having an outer perforated wall and an inner perforated wall, said walls being spaced apart, a top wall and a bottom wall for said burner head, means forming a conduit for gas from said gas generator, said conduit opening into said burner head, a movable plate-like closure in said burner head adapted to open and close the opening therein from said conduit, and means for moving said closure.
10. In an oil burner of the character described, the combination of a pair of burner heads spaced apart, a generator burner, a pipe adapted to carry liquid fuel for conversion into gas, said pipe passing in proximity to each of said burner heads and said generating burner whereby the gas flames from said burner heads and from said generating burner will play upon said pipe, a mixing chamber in communication with the interior of said generating pipe, whereby gas in said generating pipe is discharged into said mixing chamber, means for supplying air to said mixing chamber, said mixing chamber being in communication with said burner heads and with said generating burner.
11. In an oil burner of the character described, the combination of a generator pipe adapted to contain liquid fuel, a mixing chamber having means for admitting air thereinto and being in communication with said generating pipe so as to receive gas therefrom, a pair of burner heads spaced apart and on substantially the same horizontal plane, and a generator burner substantially between said burner heads and on a lower plane, each thereof being in communication with said mixing chamber whereby gas therein may be burned at said burner heads and at said generating burner, said generator pipe being positioned whereby flames from said burner heads and from said generating pipe will play upon and heat the same, the arrangement being such that liquid in said generator pipe is first partially heated by one of said burner heads, is then more completely generated into gas by said generator burner, and is then further heated by the other of said burner heads, said last mentioned burner head being adapted also to generate gas from any portion of the liquid which may pass said generator burner in said pipe.
12. The combination of a pair of burner heads supported on substantially the same horizontal plane, an elongated generating

burner positioned substantially between and below said burner heads, a substantially U-shaped generating pipe having a portion thereof overlying said generating burner and having the legs thereof in proximity to said burner heads respectively whereby gas issuing from said burner and burner heads will play upon said substantially U-shaped pipe, a manifold in communication with said generating burner and with each of said burner heads, and means for communicating gas from said generator pipe to said manifold.

13. The combination of a main support, a pair of burner heads spaced apart and carried by said support, said burner heads respectively comprising perforated inner and outer walls and top and bottom walls, an elongated generating burner substantially between said burner heads, a substantially U-shaped generating pipe having a portion thereof overlying said generating burner and having the legs thereof in proximity to

said burner heads respectively so as to be impinged by flames issuing therefrom, a manifold secured to each burner head and in communication with the hollow interior of said burner heads and said generating burner, a mixing chamber substantially intermediate said burner heads and on a materially lower plane, said mixing chamber being in communication with said manifold, said generating pipe having an extension into said mixing chamber, said extension having an opening for gas discharge, said mixing chamber having a pair of air openings, valve means for controlling the flow of gas-and-air into said burner heads respectively, valve means for controlling said air openings, and means connecting the valve means of one of said burner heads with the valve means of one of said air openings whereby said valves so connected are simultaneously operated.

ORVILLE G. HALLIBURTON.
